Patented Dec. 10, 1974

233,873

MODULAR TABLE

Floyd J. Mills, 1285 Briarcliff Road NE.,
Atlanta, Ga. 30306

Filed Dec. 7, 1972, Ser. No. 312,843

Term of patent 14 years

Int. Cl. D6—03

U.S. Cl. D6—177

FIG 1

FIG 2

FIG 3

FIG 4**FIG 5****FIG 6****FIG 7****FIG 8****FIG 9**

FIG. 1 is a perspective view of the first embodiment of the table of the present invention;

FIG. 2 is a top plan view of the table shown in FIG. 1;

FIG. 3 is a bottom side elevational view of the table shown in FIG. 2;

FIG. 4 is a perspective view of the second embodiment of the table of the present invention;

FIG. 5 is a top plan view of the table shown in FIG. 4;

FIG. 6 is a left side elevational view of the table shown in FIG. 5;

FIG. 7 is a bottom side elevational view of the table shown in FIG. 5;

FIG. 8 is a right side elevational view of the table shown in FIG. 5; and

FIG. 9 is a top side elevational view of the table shown in FIG. 5.

All side views of the first embodiment of the table embody the same configuration as shown in FIG. 2.

The left side elevational view of the second embodiment of the table embodies the same configuration as shown in FIG. 6. The top and right side elevational views of the second embodiment of the table are mirror images of FIG. 6.

I claim:

The ornamental design for a modular table, as shown and described.
